ORNAMENTAL RADIATOR CAP

Filed June 19, 1928

INVENTOR.
R. MARANZINO.

BY *B. J. Craig*,
ATTORNEY.

UNITED STATES PATENT OFFICE

ROSCOE MARANZINO, OF LOS ANGELES, CALIFORNIA

ORNAMENTAL RADIATOR CAP

Application filed June 19, 1928. Serial No. 286,511.

The general object of this invention is to provide an improved ornamental radiator cap which may be electrically illuminated.

Another object of the invention is to provide an electrically illuminated radiator cap which will not interfere with the filling of the radiator.

A further object of the invention is to provide a novel electric light socket for a radiator cap.

A still further object of the invention is to provide an illuminated radiator cap having translucent ports therein in which monograms may be placed.

Another object of the invention is to provide an ornamental illuminated radiator cap which is also adapted to support an emblem, mascot, etc.

Other objects and the advantages of this invention will be apparent from the following description taken in connection with the accompanying drawing wherein:

Fig. 1 is a side elevation of my improved radiator cap.

Fig. 2 is a top plan view of the cap.

Fig. 3 is a section taken on line 3—3 of Fig. 2.

Fig. 4 is a perspective view of one of the jewels and a monogram.

Fig. 5 is a fragmentary side view of an automobile showing my improved radiator cap thereon, and

Fig. 6 is a view of a modified form of cap, one half being shown in section.

Referring to the drawings by reference characters I have indicated my improved radiator cap generally at 10. As shown, my device 10 comprises a body portion 12 having an octagonal portion 13, a domed top 14, a reduced externally threaded neck 15 and a bottom wall 16.

Each of the faces of the octagonal portion 13 is provided with an aperture 17 in which a translucent glass or jewel 18 is adapted to be secured by a suitable cement as indicated at 19. To the rear of some or all of the jewels 18 I preferably secure, as by gluing thereto, an opaque disk 20 having a letter or emblem 21 cut therein (see Fig. 4).

The domed top 14 is preferably provided

with a central aperture 22 in which a shank 23 of an emblem or mascot 24 is adapted to be positioned and the mascot 24 may be secured to the device 10 by a nut 25.

Arranged around the central aperture 22 in the dome 14 I preferably provide a plurality of apertures 26 in which translucent jewels 27 are adapted to be positioned similar to the jewels 18.

The bottom wall 16 is provided with a central screw threaded aperture 28 in which a reduced screw threaded portion 29 of a cup shaped member 30 is adapted to be positioned. The member 30 includes a wrench gripping portion 31 and a bottom wall 32.

The member 30 also includes a recess 33 threaded as at 34 adjacent its open end and an aperture 35 in the bottom wall 32 which communicates with the recess 33.

A lamp socket 36 having an externally screw threaded portion 37 and a wrench engaging portion 38 is adapted to be positioned in the screw threaded portion 34 of the recess 33. The lamp socket 36 includes a central aperture 39 in which the base 40 of an electric lamp 42 is adapted to be positioned. Grooves 43 are provided in opposite faces of the aperture 39 in which the lugs 44 on the lamp base 40 are adapted to move when the lamp is inserted or removed from the socket 36. The lamp 42 is adapted to be positioned in the socket 36 so that the lugs 44 engage the bottom surface of the socket as shown in Fig. 2.

A contact holder 45 made of an insulating material is positioned in the recess 35 of the member 30 and includes a reduced portion 46 which extends through the aperture 35 in the bottom wall 32. Within a central aperture 47 in the holder 45 a metal contact 48 is positioned and is adapted to be retained in the holder by means of a screw 49 which is positioned in an aperture in the holder and a screw threaded aperture in the contact. The contact 48 includes a central aperture 50 in which a wire 51 is adapted to be positioned. This wire 51 is adapted to be securely held in position in the contact by the screw 49 which holds the contact to the holder. The wire is adapted to be held in position in the

holder 45 by a screw 52 positioned in the reduced portion 48 thereof and adapted to engage the wire covering as shown. A coiled spring 53 is adapted to be positioned over the 5 end of the contact 48 and is adapted to engage the center contact 54 of the electric lamp.

In Figs. 2 and 5 I have shown the device 10 as positioned on the filling neck 55 of a radiator 56 of an automobile 57. The radiator 56 may be of any type and is shown as including an overflow pipe 58 in which the wire 51 is preferably run to a source of power such as the battery of the car.

15 When the device 10 is operatively positioned on an automobile radiator as shown in Figs. 2 and 5 and the electric current is turned on to illuminate the lamp 42 the rays from the lamp will pass through the apertures 17 and 26 and illuminate the jewels 18 and 27. When the lamp is lit the monograms will be illuminated and the reflected rays from the jewels 27 in the dome will also play upon the mascot.

25 In Fig. 6 I have shown the member 30 positioned in a modified form of radiator cap indicated generally at 60. This cap includes a cylindrical body portion 61 having a domed top 62 and a bottom wall 63 which has a 30 downwardly extending enlarged cylindrical flange 64.

The flange 64 is internally threaded as at 65 to engage external screw threads on a filling neck 66 of an automobile radiator 67 and 35 the bottom wall 63 is provided with a central screw threaded aperture 68 in which the threaded portion 29 of the member 30 is adapted to be positioned.

The body portion 61 and the dome 62 of 40 the device 60 is provided with a plurality of apertures 69 in which translucent jewels 70 are adapted to be positioned similar to the jewels in the device 10.

Monogram disks 72 similar to the monogram disks 20 shown in Fig. 4 are also provided in a plurality of the apertures 29.

The device 10 may be constructed to fit an externally threaded filling neck and the device 60 may be constructed to fit an internally 50 threaded filling neck.

From the foregoing description it will be apparent that I have provided a novel and efficient ornamental radiator cap for automobiles which can be economically manufactured and quickly installed.

Having described my invention, I claim:

1. An automobile cap comprising a body portion, a domed top and a bottom wall, a plurality of apertures in said body, a translucent closure in each of said apertures, a plurality of apertures in said top and a translucent closure in each of said apertures, a cup-shaped member supported by said bottom wall, a socket in said cup-shaped member, an electric lamp positioned in said socket,

a holder positioned in said member, said holder having a central aperture and a contact positioned in said holder aperture.

2. In an automobile cap, a body portion, a domed top and a bottom wall, a plurality of apertures in said body, a translucent closure in each of said apertures, an opaque member behind certain of said closures, said opaque members having symbols therein, a plurality of apertures in said top and a closure in each of said apertures, a cup-shaped member in said body, a lamp socket in said body supported by said member, said member being supported by said bottom wall, an electric lamp positioned in said socket, a holder positioned in said member and having a central aperture, a contact positioned in said holder aperture, a central aperture in said contact, a wire positioned in said contact aperture, a transverse aperture in said holder and a corresponding transverse aperture in said contact, means adapted to be positioned in both of said apertures and adapted to hold said contact to said holder, another transverse aperture in said holder, means in said last mentioned aperture adapted to engage said wire and hold said wire to said holder and a coiled spring, said spring being positioned over the end of said contact and engaging the center contact of said lamp.

3. A cap for an automobile, said cap comprising a multi-sided body portion, a domed top and a bottom wall, an aperture in each of said body sides, a translucent closure in each of said apertures, an opaque member behind certain of said closures, said opaque members having symbols therein, an aperture in said domed top adjacent the center thereof and means positioned in said aperture to receive an emblem, a plurality of other apertures in said top arranged around said central apertures, a translucent closure in each of said other apertures, said bottom wall having a screw threaded aperture, a cup shaped member positioned in said threaded aperture, said member being threaded adjacent its open end, said member including a bottom wall, an aperture in said bottom wall, a lamp socket, said socket including a reduced threaded portion positioned in said screw threaded portion of said member, said socket including a central aperture, an electric lamp, said lamp including a base having lugs thereon, oppositely disposed grooves in said socket in which said lamp lugs are adapted to move when said lamp is being inserted or removed from said socket, said lamp base lugs being adapted to engage the under face of said socket when operatively positioned therein, a holder positioned in said recess of said member, said holder including a reduced portion positioned in said aperture in said bottom wall of said member, a central aperture in said holder, a contact positioned in said holder aperture, a central aperture in

said contact, a wire positioned in said contact aperture, a transverse aperture in said holder and a corresponding transverse aperture in said contact, means positioned in both of said apertures to hold said contact in said holder, means in said last mentioned aperture to engage said wire and hold said wire in said holder and a coiled spring positioned over the end of said contact and engaging the center

10 contact of said lamp.

4. In an automobile cap comprising a hollow body portion, a hollow cup shaped member engaging said body portion and including an apertured bottom wall, a holder secured to 15 said member, a lamp socket removably secured in said holder, said holder including a hollow portion, said holder having an aperture therein, a contact rotatably mounted in said holder aperture and a wire connected to 20 said contact.

5. An automobile cap comprising a body portion having an apertured bottom wall, a hollow member, said member having a reduced portion rigidly engaging within said 25 body aperture, said member including a bottom wall having an aperture therein, a lamp socket positioned in said member, an electric lamp positioned in said socket, a holder rotatably mounted on said member, said holder including a contact and a wire connected to said 30 contact.

6. In an automobile cap, a body portion having a domed top, a bottom and a polygonal side wall, said polygonal side wall having a 35 plurality of apertures therein, a translucent closure in each of said apertures, said top having an aperture therein, a translucent closure in said top aperture and a figure secured to said top in position to be illuminated 40 by light passing through said top translucent closure.

In testimony whereof, I hereunto affix my signature.

ROSCOE MARANZINO.
